UNITED STATES PATENT OFFICE.

ROBERT T. BURRILL, OF WINCHESTER, NEW HAMPSHIRE.

RAIL-TIE.

1,270,691.

Specification of Letters Patent. Patented June 25, 1918.

Application filed May 25, 1917. Serial No. 170,927.

To all whom it may concern:

Be it known that I, ROBERT T. BURRILL, a citizen of the United States, residing at Winchester, in the county of Cheshire and 5 State of New Hampshire, have invented certain useful Improvements in Rail-Ties, of which the following is a specification, reference being had therein to the accompanying drawing.

10 The present invention has reference generally to improvements in that class of inventions known as ties and fasteners and more particularly has reference to an improved tie.

15 As the primary aim and object this invention contemplates the provision of a metallic tie in which is mounted improved rail seating means so that the tie will have the characteristics of the usual wooden tie 20 and yield a slight extent when the rolling stock is passing over the rails.

It is an additional and equally important 25 object to provide novel rail fastening means mounted on the tie for holding rails on the seating means and for preventing accidental movement of the seating means subsequent to being arranged in the proper position.

More particularly, the present invention 30 includes the provision of novel means for reinforcing the ends of the tie adjacent the seating means to reduce the possibility of the tie becoming broken, thus obviating the spreading of the rails.

35 Among the other aims and objects the present invention includes the provision of a device of the character mentioned with a view to compactness, and in which the parts are few, the construction simple, the cost 40 of production low and the efficiency high.

Other objects as well as the nature, characteristic features and scope of this invention will be more readily apparent from the following description taken in connection 45 with the accompanying drawings and pointed out in the claims, forming a part of this specification.

The preferred embodiment of the present invention is clearly illustrated in the accompanying drawings, in which:—

Figure 1 is a top plan view of one form of the invention.

Fig. 2 is a fragmentary perspective thereof.

Fig. 3 is a fragmentary perspective of the 55 invention showing another form of means for fastening the rails, and

Fig. 4 is a detail of the form shown in Fig. 3 illustrating the means for preventing accidental movement of the seating 60 means or wood blocks.

Similar characters of reference are employed in all of the above described views, to indicate corresponding parts.

Referring now, more particularly, to the 65 accompanying drawings there is provided a tie including a hollow metallic body 1 preferably rectangular in cross section, the top and side walls of the body adjacent the respective ends being cut away to provide 70 transverse rail receiving recesses 2, the body being also provided in the top and in spaced relation to the opposite sides of each recess with transverse slots 3 which are also arranged diagonally with respect to each other 75 for a purpose that will presently appear.

In order to reinforce the respective ends of the tie at the recesses so as to obviate any breakage of the bodies at these points improved reinforcing means have been provided. In the present instance a rectangular plate 4 is provided and has a slot 5 therein so that when the plate is bent in a substantially U-shaped form and straddled about the top and side walls of the tie, the 80 ends of the slot 5 are arranged in alinement with the bottoms of the recesses in the side walls as indicated in the drawing, suitable fastening devices 6 being provided for holding the reinforcing plate in this position on 85 the tie body.

With a view toward providing the improved rail seating means, in the present instance wood blocks 7 are employed, said blocks being insertible in the respective 95 ends of the tie so as to extend across the recesses 2. As is apparent the blocks are of a similar configuration and are snugly engaged with the side walls of the top and bottom of the body on the inner surface 100 thereof while the blocks are slightly longer than the width of the recesses so as to lie beneath the recesses and serve as a means for supporting the bases of the rails 8 in a

manner so that the base flanges 9 thereof will be approximately flush at their outer side edges with the upper surface of the top as shown in Fig. 2.

5 As intimated improved means have been provided for fastening the rails in a substantially rigid position on the tie and for preventing accidental displacement of the blocks 7. This improved means consists of 10 bearing brackets 10 which have rotatably mounted therein the rail base flange engaging portions 11 of the improved right angular bolts indicated in their entirety by the numeral 12. The slot engaging portions 13 15 on account of their weight are normally adapted to be arranged through the slots 3 and in close relation with the opposite ends of the block 7 as indicated in Fig. 2. These portions 13 incidentally coöperate with the 20 slots and serve as a lock for the portion 11 for preventing longitudinal movement thereof. In releasing the rails 8 a suitable implement may be inserted in the slot to raise the portion 13 out of the slot 3 and obviously by 25 pulling the portion 13 away from the bracket the portion 11 will be disengaged from the base flange 9.

In the form of the invention illustrated in Fig. 3, the parts are all similar to the parts 30 shown in Figs. 1 and 2, however with the exception of the rail fastening means. In this form, instead of employing the right angularly bent bolts 13, bearing brackets 14 are rigidly mounted by suitable fastening devices 35 15 vertically on the side walls of the tie adjacent the sides of the recesses as indicated, the brackets being arranged also upon opposite sides of the rails. Bolts 16 are inserted in the bearing brackets so that the heads 17 40 thereof engage the lower edges of the brackets while the outer threaded extremities are engaged by washers 18 and nuts 19 the latter serving to clamp the washers against the base flanges of the rails to prevent 45 the same from becoming accidentally displaced. This form of the invention also includes the wedges 20 which are arranged on the upper surfaces of the bottoms of the body longitudinally thereof and out of alignment with each other. One of the blocks 21 is provided with a longitudinal groove 22 to permit of the body to be inserted at one end and ride freely past one of the wedges and permit of the block to be moved through the 50

body until it engages the other wedge which maintains it in a proper position beneath the recess as indicated in Fig. 3.

In view of the foregoing description it is thought that a detail description of the operation of the invention is unnecessary. Likewise it is believed that the advantages of the invention will be readily apparent.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages 70 of my invention.

Having thus fully described my invention, what I claim as new and desire to secure by Letters-Patent, is:—

1. A tie including a hollow metallic body 75 having the top and side walls cut away adjacent the respective ends to provide rail receiving recesses, means for reinforcing the body at the recesses, rail supporting blocks arranged in the respective ends of the body and 80 positioned beneath the recesses, the tops of the ties being provided with slots on opposite sides of each recess, bearings mounted on the upper surface of the tops and right angularly bent bolts journaled in the bearings 85 and engaging the slots for preventing longitudinal movement of the blocks and adapted for retaining rails on the tie.

2. The combination with a hollow tie having rail receiving recesses adjacent the respective ends thereof and further provided with slots on opposite sides of each recess, blocks insertible in the body and positioned beneath the recesses, rails arranged in the recesses and supported by the blocks, of 90 brackets mounted on the upper surface of the tie upon opposite sides of each recess and in staggered relation, right angled bolts having rail engaging portions journaled in the brackets for retaining the rails in position 100 and having the opposite portions arranged through the slots and in close relation with the respective ends of each block for preventing movement of the blocks and also for preventing accidental longitudinal movement of 105 the rail engaging portions in the brackets.

In testimony whereof I affix my signature.

ROBERT T. BURRILL.
